SPRAYING APPARATUS

Paul J. Timberlake, Jackson, Mich.

Application December 13, 1937, Serial No. 179,467

8 Claims. (Cl. 299—88)

The present invention relates to a spraying and hot air drying device which has particular application in the servicing of automotive vehicle transmission and differential casings, but which also has general application including the applying of certain coating materials and drying them.

An object of the invention is to provide a device for heating air under pressure and utilizing the heated air to heat oil or a coating material, and at the same time to draw the oil or coating material from a container.

Another object of the invention is to provide a device having a nozzle from which at will may be directed hot air or a sprayed liquid.

A still further object of the invention is to provide a combined spraying and hot air blowing device having a nozzle provided with structure to prevent under predetermined conditions its removal from the filling opening of a transmission or differential casing or other opening into which it has been inserted.

These and other objects will be apparent from the following specification when taken with the accompanying drawing, in which:

Fig. 1 is a partial vertical section of the structure comprising the invention.

Fig. 2 is an enlarged view of a valve.

Fig. 3 is an elevation of a retaining hook associated with the spraying tip.

Fig. 4 is an elevation of a safety screen disposed in the air gun adjacent the outlet thereof.

Fig. 5 is a vertical section of an alternative structure for securing the nozzle to the air gun, and

Fig. 6 is a section of a form of nozzle arranged for quick cleaning.

Referring particularly to the drawing, reference character 1 indicates an air gun such as is described in my co-pending application Serial No. 105,917, filed October 16, 1936. The air gun comprises end frames 2 and 3, between which is mounted an electric heating element 4 connected to an electric power line 5 and surrounded by a heat insulating casing 6 and an expanded metal guard 7. Compressed air is admitted to the gun from a suitable source through a fitting 8 controlled by a shut-off valve 9. As in my aforesaid co-pending application, the compressed air passes into the interior of the gun past the inlet end of the heating element 4 and is heated. The heated air is discharged past the outlet end of the heating element 4 into a threaded passage 10 in the end frame 2 at the outlet end of the gun.

The aforesaid structure is substantially the same as that of my above mentioned co-pending

application. The present invention comprises the combination with said air gun of the heating and spraying device to be described, as well as the particular structure and features of the heating and spraying device.

A nozzle 15 comprising a suitable tube is threaded at one end to the end frame 2 and at the other end has threaded thereto a spraying tip 16. The nozzle 15 has connected thereto a tube 17 which passes through the wall of the nozzle 15 and extends inside thereof to ejecting relationship with the tip 16. The interior bore of the spraying tip 16 and the end of the tube 17 associated therewith are provided with tapers 18 and 19, respectively, so that as the tip 16 is adjusted axially with respect to the nozzle 15 the characteristics of the spray which is produced are varied.

The tube 17 is connected through a valve 20 to a small container 21, the container 21 in actual practice having a capacity of one pint, more or less, although it is to be understood that the size of the container 21 is not a limiting feature of the invention. The container 21 is enclosed at its rear end with a concave plate 22, at the mid-portion of which is threaded a filling plug 23. The concavity of the plate 22 is for the purpose of facilitating the filling of the container 21 when the same is up-ended. A tube 24 within the container 21 communicates with the valve 20 and projects to the lower rear portion of the container 21 in order that liquid therein may be as completely used up as possible.

The valve 20 has provided in the body thereof a passage 29 for conducting liquid from the container 21, the passage 29 being in alignment with a port 30 in the valve member 31 of the valve 20. The body of the valve 20 is also provided with a passage 32, which is in alignment with a port 33 in the valve member 31 of the valve 20. The function of the passage 32 and the port 33 is to permit the inlet of air to the container 21 as liquid is withdrawn therefrom. The valve 20 is controlled by a thumb piece 34, and its movement is limited by a pin 35 movable with the valve member 31 thereof in a slot 36 in the valve body. A spring 37 is employed to maintain the valve member 31 seated in the body of the valve 20 in the usual manner. It will be understood that in operation the rotating of the valve member 31 by the thumb piece 34 will simultaneously open or close the passages 29 and 32 to the flow of liquid and air, respectively.

The nozzle 15 is provided adjacent the outer end thereof with a relatively fixed flange 40 and

has slidable thereon between the flange 40 and the tip 16 a rounded seat 41. A spring 42 is disposed on the nozzle 15 between the flange 40 and the seat 41 to urge the seat 41 toward the tip 16.

Associated with the tip 16 is a hook 43 which, as shown particularly in Figs. 1 and 3, comprises a flat washer like plate 44 having a threaded internal opening 45 and an extended side 46, the end of which is turned over to provide the hook 43. The hook 43 is disposed between the seat 41 and the tip 16 and is threaded on the outer end of the nozzle 15 to abutting relation with the tip 16.

At the inner side of the end frame 2 is disposed a metallic screen 47 to prevent the flame of any oil or other vapors which may have ignited, either within or without the interior of the hot air gun 1, from passing outwardly or inwardly with respect to the interior of the hot air gun 1. The screen 47 is generally semi-spherical in shape and is secured to a bushing 48 provided with a seat 49. The interior of the bushing 48 is preferably hexagonal in cross-section, and the exterior is threaded to threadably engage the threaded passage 10. The bushing 48, after being manually threaded into the threaded passage 10, may be taken up, by means of an internally acting wrench, to urge the seat 49 against the interior face of the end frame 2 to secure the bushing 48, and thus the screen 47, in position.

The container 21, while somewhat supported by the tube 17, is additionally supported by a bracket 55 which is in the form of a metallic band which is clamped by means of a bolt 56 about the container 21. The bracket 55 has an extension 57, which is flared out and provided with an opening through which the nozzle 15 is passed. The extension 57 is disposed on the nozzle 15 between the movable nut 58 and the nut 59 fixed with respect to the end frame 2. Thus, after the nozzle 15 has been threaded into the threaded passage 10, taking up on the nut 58 not only clamps the bracket 55 to the hot air gun 1 but also locks the nozzle 15 in the threaded passage 10.

In Fig. 5 is disclosed an alternative form of connection between the nozzle 15 and the end frame 2. In this form there is threaded into the threaded passage 10 a sleeve 65 having an outwardly extending portion 66 provided with bayonet slots 69. The inner end of the nozzle 15 is provided with an enlarged extension 68 provided with pins 67, by means of which in cooperation with the slots 69 the nozzle 15 is secured to the end frame 2. The bracket 55 supporting the container 21 is provided with a clamping ring 71 which is clamped to the extension 68 by a bolt 72. The nozzle 15 is assembled on the tubular extension 66 by loosely fitting the bracket 55 on the container 21 and the clamping ring 71 over the nozzle 15 and turning the pins 67 into the slots 69. The bolts 56 and 72 are then tightened to provide a rigid support for the container 21.

The foregoing structure, while primarily designed for cleaning and flushing transmission and differential casings of automotive vehicles, may be used for a variety of purposes. In its use for servicing transmission and differential casings, the tip 16 and the hook 43 are disposed within the filling opening of the casing to be serviced, the hook 43 being manipulated to engage a portion of the inner surface of the casing. The seat 41 bears against the outer edge of the opening and is yieldably urged thereagainst by the spring 42, the hook 43 opposing the action of

the spring 42. The valve 20 is closed at the start of the servicing operation to close off the communication with the container 21, which has previously been filled with any suitable grade of flushing oil or the like. The heater is turned on, and compressed air is admitted by opening the valve 9. Hot air is then projected into the interior of the casing, its escape through the filling opening being prevented by the seat 41. By manipulating the nozzle 15 through the air gun handle 70, hot air may be directed against different portions of the interior of the casing to soften and loosen heavy grease therein. The valve 20 is then opened. Oil from within the container 21 is drawn through the tubing 17 by the ejecting action of the air passing through the tip 16 and is sprayed by the tip 16 into the interior of the casing. As the oil from the container 21 passes through the portion of the tube 17 within the nozzle 15, the hot air heats the oil so that an oil spray of high temperature is provided. The nozzle 15 may be appropriately manipulated to direct the spray against different interior surfaces of the casing. After the flushing with the hot spray has been completed, the valve 20 is closed and a blast of hot dry air is directed into the interior of the casing to dry the same. The servicing is then completed, and the tip 16 and hook 43 are withdrawn from the filling opening.

The present invention also has particular utility in applying coating materials which must be applied either hot or cold and which can be dried expeditiously with heat. In applying a coating material, the container 21 is filled with the coating material and is sprayed in the manner hereinbefore described by opening the valve 20 and compressed air valve 9, either with or without heat, as the specific coating material requires. The valve 20 is then closed and hot air applied to dry the coating after it has been applied.

It will be clear that, in the use of the foregoing structure, when different materials are used a separate nozzle 15 and container 21 assembly may be employed for each material used. Thus one assembly would be used for flushing oil, another assembly for blue lacquer, etc.

In Fig. 6 is disclosed an alternative form of nozzle and tip arrangement for use particularly when a coating material is used. Coating materials have a tendency to build up on the inside of the tip, thereby hindering the spraying operation. The nozzle 15 is provided with a threaded portion 73 adjacent the end thereof and at the end thereof is provided with a cylindrical portion 74, about which telescopically fits a tip 75. The tip 75 abuts against a washer-like member 76, threaded to the portion 73, which determines the relative axial position of the tip 75 with respect to the tapered end 19 of the tube 17. It will be clear that by movement of the washer-like member 76 along the threaded portion 73, the adjustment of the tip 75 with respect to the tapered end 19 of the tube 17 may be changed. Secured to the tip 75 are oppositely projecting trunnions 77, to which are pivoted links 78. The links normally urge the tip 75 against the washer-like member 76, but when it is desired to clean the interior of the tip 75 the links 78 are moved downwardly to disengage the tip 75 from relation with the tapered end 19 of the tube 17. Air blowing through the nozzle 15 will then dislodge any coating material adhered to the interior of the tip 75 and clean the same. By actuating the links 78 to move the tip 75 back against the

washer-like member 76, the tip and nozzle assembly are placed in condition for use again.

Having thus described my invention, what I desire to secure by Letters Patent and claim is:

1. A device of the character described comprising a hot air gun having a nozzle, a spraying tip on the outer end of said nozzle, a tube within in a portion of said nozzle and communicating with said tip in ejecting relation thereto, a source of liquid communicating with said tube, means to connect a source of compressed air to said gun, whereby said air, heated in said gun, draws said liquid into said tube, heats said liquid in said tube and sprays the same from said tip, a spring pressed sealing member associated with said tip and a hook associated with said tip, whereby when said tip is disposed through an opening in a casing said hook may be made to engage the inner wall thereof to prevent outward movement of said tip, and said sealing member engages with the outer wall thereof.

2. A device of the character described comprising a hot air gun having a nozzle, a spraying tip having a connection to the outer end of said nozzle, a tube within a portion of said nozzle and communicating with said tip in ejecting relation thereto, a source of liquid communicating with said tube, said source comprising a closed portable container supported from said gun, means to connect a source of compressed air to said gun, whereby said air, heated in said gun, draws said liquid into said tube, heats said liquid in said tube and sprays the same from said tip, and a valve to control the flow of liquid from said source, said valve having a passage for the outlet of liquid and a separate passage for the inlet of air to said container.

3. A device of the character described, comprising a hot air gun having a detachable nozzle, a spraying tip on the outer end of said nozzle, a source of liquid, said source comprising a portable container, a fluid connection from said source to said tip in ejecting relation thereto, means to connect a source of compressed air to said gun, whereby said air heated in said gun draws liquid into said tube and sprays the same from said tip, means to transfer heat from said hot air to said liquid, a valve to control the flow of liquid from said source, and means to support said container from said gun, said means comprising a bracket secured to said container and clamped between said nozzle and said gun.

4. A device of the character described for directing a spray through a restricted opening into a chamber, comprising a spraying tip, a spring pressed sealing member concentric with and axially slidably along the axis of said tip, and a hook fixedly supported upon said tip, said hook being adapted to be disposed through said restricted opening into said chamber and to bear against the interior of said chamber, and said sealing member being adapted to yieldably bear

against the outside of said chamber to seal said restricted opening, the reaction to said spring pressed sealing member being resisted by said hook.

5. A portable combination hot air and liquid spraying gun comprising an air heating chamber, an elongated conduit connected to said chamber at one end and having a nozzle at the other end, a tube for conducting liquid to said nozzle, said tube being housed for a portion of its length in said conduit in heat exchanging relation and having a tip portion adjacent said nozzle so located as to be in a zone of reduced pressure when hot air is passed through said conduit, a liquid container supported in unitary relation with said chamber, but exteriorly of said chamber and conduit with which said tube connects, and means to connect said chamber to a source of compressed air whereby said air, heated in said chamber, draws said liquid into said tube, heats the liquid in said tube and sprays the same from said tip through said nozzle.

6. A compact portable combination hot air and liquid spraying gun having a heating chamber, 25 a pistol grip connected exteriorly of said chamber with a substantial portion of said chamber projecting forwardly of said grip, a threaded outlet opening at the outer end of said chamber, a removable nozzle threadedly supported in said opening, a tank for spraying liquids supported from said nozzle and constituting a unitary part thereof, said tank with the nozzle in position overlapping that portion of said chamber forwardly of the pistol grip, said tank being sufficiently spaced from a portion of said nozzle threaded into said opening as to clear said chamber when the nozzle is secured to the chamber by relative rotation between the nozzle and chamber, and conduit means for conveying liquid from said tank to said nozzle.

7. A removable spraying nozzle assembly for hot air guns comprising an elongated conduit portion for connection with a hot air chamber of an air gun, a tube for the spraying liquid having 45 a portion of its length housed in said conduit portion in heat exchange relation, one end of said tube having a spraying tip adjacent the end of said nozzle, a tank for the spraying liquid unitarily associated with said conduit portion, the other end of said tube being connected to said tank.

8. A removable spraying nozzle adapted to be threaded into the barrel of a hot air gun comprising a nozzle portion, a tank, bracket means extending between the threaded end of said nozzle and the tank to position said tank rearwardly of the threaded portions of said nozzle sufficiently to one side of the axis thereof to enable the tank to clear the barrel of the gun at the time the nozzle is threaded into position, and conduit means between the tank and nozzle.

PAUL J. TIMBERLAKE.
